PRESSURE FLUID MOTOR

Wade H. Wineman, Coolspring Township, La
Porte County, Ind., assignor to Sullivan Ma-
chinery Company, a corporation of Massa-
chusetts

Application September 28, 1936, Serial No. 102,990

20 Claims. (Cl. 121—132)

My invention relates to motors, and in certain aspects thereof more particularly to pump actuating motors. From another aspect it relates to cushioning devices.

Mechanical pumping of oil wells is necessary when the stratum pressure is inadequate to raise the oil to the surface, and a very successful pumping apparatus used for this purpose includes commonly a central source of motor fluid supply, together with a number of expansible chamber motors, actuated by the fluid supplied from said central source and each operating a pump arranged in the well through a sucker rod line. In such a system a pressure of from 200 to 300 pounds, say, per square inch is employed for effecting the working strokes of the pump operating motor, and the motors exhaust against a back pressure of from 50 to 100 pounds per square inch, said back pressure being so determined as to retard in a suitable manner the downward movement of the motor piston and the parts supported thereby. The pumping unit at each well commonly comprises a single-acting expansible-chamber motor provided with a fluid-actuated valve mechanism, and these motors have associated with them dash pot or cushioning means so that in the event that their pistons lose their loads, due, for example, to sucker rod line breakage or to the rupturing of a pump packing or the like, the upward movement of the motor piston and the attached portion of the pump rod line may not seriously damage the apparatus in its uncontrolled upward movement. Apparatus for shutting off the motor fluid supply to said pumping motors, in the event of their making a stroke not under normal working conditions, has been devised and patented by me, see Patent No. 2,004,145, and this apparatus is effective to shut down the pumping motor in the event of a breakage of the pump rod line or the rupture of a pump packing, and to protect the system save for one possible factor. When the motor over travels at high velocity, as would occur when the sucker rod line breaks, quite a substantial pressure will be built up in the cushion cylinder, and at the end of the cushioning of the rising motor piston this pressure will tend to drive back down the motor piston and its connected parts and perhaps cause serious damage during said downward movement of these parts. It would accordingly make a device which would be practically proof against any further serious injury, in the event of the rupture of a sucker rod line, if after the cushioning effect has been availed of, the cushion pressure might be quickly bled away before it would have an opportunity to im-

part a substantial downward momentum to the motor piston and supported parts. I have devised an apparatus for this purpose, effective upon the completion of cushioning to relieve the cushion pressure; and in the form of the invention herein disclosed have rendered this pressure relief mechanism responsive to pressure changes within the cushion cylinder, although it will be obvious that other and radically different control means might be devised within the scope of my invention. 5 With this apparatus I have incorporated another mechanism which per se forms the subject matter of a separate application (Serial No. 102,989), to-wit: means for locking the fluid distributing valve in exhaust-effecting position when the sucker rod line or a packing is ruptured, and thereby have provided a very simple and effective complete shut-down device for stopping the pumping motor without any harm whatever after such a rupture takes place. 20

It is an object of my invention to provide an improved motor. It is another object of my invention to provide an improved pump-operating motor having improved cushioning means. It is a further object of my invention to provide an 25 improved pump-operating motor, having associated therewith means for cushioning the motor in the event of the loss of load of the motor piston, and for venting the cushion pressure before the same has an opportunity to impart to the motor system, as the cushion pressure fluid tends to re-expand, a high or detrimental velocity. It is yet a further object of my invention to provide an improved motor having associated therewith improved means operative upon material over-travel of the motor piston to interrupt the operation of the fluid distribution means for the motor, to cushion the abnormal motor piston movement, and to release the cushion pressure which is built up in order that the motor may come to rest 30 without detriment to itself or to supported and actuated parts. It is yet a further object of my invention to provide an improved pumping motor having associated therewith improved cushioning means and improved distributing valve controlling 35 means in order that cushioning of the motor may be effectually accomplished and the motive fluid distribution to the motor interrupted and the cushion pressure released so that no violent downward movement of the motor piston and supported parts will take place. Still another object is to provide an improved cushioning device. Other objects and advantages of the invention will hereinafter more fully appear. 40

In accompanying drawings, in which, for pur- 55

poses of illustration, one embodiment which my invention may assume in practice has been shown,

Fig. 1 is a view in front elevation showing a pumping motor of the character hereinabove mentioned incorporating my invention in its illustrative form.

Fig. 2 is a vertical section on a plane corresponding to the section line 2-2 of Fig. 1, some parts being shown in elevation.

10 Fig. 3 is a section, with parts broken away, on a still further enlarged scale, and on a plane corresponding to the section line 3-3 of Fig. 2, showing details of the distributing valve mechanism and of the automatic control therefor.

15 Figs. 4 and 5 are sectional views on an enlarged scale through the automatic control device associated with the distributing valve, these sections taken on a plane corresponding to the plane of Fig. 2, and respectively showing the automatic control device in its normal position and in its position assumed upon a predetermined over travel of the motor piston.

20 Fig. 6 is a horizontal section on a plane corresponding to the line 6-6 of Fig. 3.

25 Fig. 7 is an enlarged vertical sectional view on the plane of the section line 7-7 of Fig. 1, through the automatic cushion pressure release device.

30 Fig. 8 is a similar view showing the cushion release device about to release the cushion pressure.

Fig. 9 is a similar view showing the release of cushion pressure in progress.

35 Fig. 10 is an enlarged fragmentary section showing a portion of the cushion release mechanism.

Fig. 11 is a horizontal section on the plane of the line 11-11 of Fig. 10.

40 Referring to the drawings, it may be noted that a suitable support 1, of which but a portion is shown, has pivotally connected thereto at 2 the upper head 3 of a pumping motor which is generally designated 4. Such pumping motor includes, in addition to its upper head 3, a lower head 5, a cylinder 6 having a bore 7, a piston 8 reciprocable in said cylinder bore and having a piston rod 9, and a fluid distribution mechanism generally designated 10.

45 The motor cylinder 6 comprises a portion 6a between whose ends the piston 8 is reciprocable during normal pumping operations, and an aligned cylinder portion 6b which constitutes a dash pot or cushion cylinder; and a suitable automatic release valve device 11, which forms a portion of the subject matter of my co-pending application, Serial Number 102,987, being filed concurrently herewith, is arranged to permit breathing of the pumping cylinder during normal pumping operations without the building up of a differential in pressure between the interior and exterior thereof, exceeding 1 or 2 pounds per square inch. Said automatic relief valve device is adapted, however, as more fully explained in my co-pending application, substantially to interrupt the discharge of air from above the motor piston in the event that upward motor piston movement should commence to take place at an excessively rapid rate as, for example, a result of the loss of the pumping load on said motor, due either to sucker rod line breakage, or to the rupturing of a pump plunger packing, or the like. Obviously, by providing a long enough pump cylinder in the well, it is possible to permit the piston rod 9 to impart to the pump plunger pumping strokes of consider-

able length during normal pumping operations, and also to permit further upward movement of the pump plunger without damage to the pump, should a pump packing break—sufficient to enable cushioning and bringing to rest of the motor piston 8.

The distributing valve mechanism 10 forms a portion of the subject matter of my co-pending application, Serial Number 102,987, above mentioned. A description thereof in minute detail

10 is, therefore, unnecessary in this case, but a sufficient description is desirable to enable the mode of operation of the device and its manner of co-operation with some of the auxiliary devices employed therewith to be followed entirely within the confines of this case. The lower motor cylinder head 5 has a projecting portion 15, in which there are formed a fluid supply space 16, a fluid exhaust space 17 and an intermediate space 18 connected through a port 19

20 with the lower end of the cylinder bore 7. Fluid, desirably at pressures of say 200 to 300 pounds per square inch in the case of wells of substantial depth, may be supplied to the space 16 through a connection 20, and fluid may be exhausted from the space 17 by way of a connection

25 to a system in which a relatively constant back pressure of say about 50 to 100 pounds per square inch, depending upon the depth of the well and other factors, may advantageously be maintained. A suitable bore 23 is formed within the projecting portion 15 of the lower cylinder head 5, and receives a liner and valve-chamber-forming member 24, which is appropriately

30 shouldered to position the same against downward longitudinal movement beyond the desired position, in the projecting portion 15 of the cylinder head. An upper head 25 engages the upper end of the member 24 and closes the latter and also serves, together with appropriate

35 clamping elements 26, to secure the member 24 in the desired position with respect to the lower cylinder head 5. A lower head element 27 is secured in a position to close the lower end of the bore 23, and has a projecting portion 28 of reduced diameter, which fits into and closes the lower end of the bore within the element 24. The element 24 has a stepped bore formed therein, the lower, longer portion of which is designated 30 and the upper, shorter and larger portion of which is designated 31. By the provision

40 of clearance, as at 32, around the lower end of the member 24 and the formation of a passage 33 in the member 27, continuous communication is obtained between the space 17 and the lower end of the distributing valve shortly to be

45 described, and the distributing valve is continuously subjected to motor back pressure.

46 A distributing valve 35 is reciprocable within the bore of the member 24 and has an upper, 50 relatively short, larger head 36 fitting the bore 31 and reciprocable therein, an intermediate head 37 spaced from the head 36, and a lower head 39 spaced by a fluid conducting groove 38 from the head 37, heads 37 and 39 fitting the bore 30.

55 Since the lower end of the distributing valve is continuously subjected to motor back pressure—a pressure which ranges commonly from 50 to 100 pounds depending upon the installation—it is obvious that reciprocation of the fluid distribution valve may be controlled by effecting variations in the pressure acting upon the upper head of said valve. So long as pressure acting

60 on said upper head is equal to or greater than the

65

70

75

80

85

90

95

5 pressure acting upon the lower head 39, the fluid distribution valve will occupy a position corresponding to that shown in Fig. 2. When, however, the pressure acting upon the upper head of the valve is reduced to substantially atmospheric pressure, the fluid distribution valve will be moved upwardly into a position to effect a supply of motor fluid to the lower end of the motor cylinder from the groove 16, through the groove 38 in the 10 valve, through the space 18 and port 19, into the 15 lower end of the cylinder.

10 Means is provided whereby the movements of the motor piston 8 may control the supply and exhaust of fluid relative to the space above the 15 upper head 36 of the distributing valve, and means controlled by the movements of the valve itself are provided in order that a proper cycle of operation may be secured. From a point 40 in the cylinder bore 1, uncovered by the lower end 20 of the upwardly moving piston 8, just as the latter approximately reaches the desired upper limit of its working stroke, there is extended a connection 41, leading to the upper head element 25 of the distributing valve mechanism. Within 25 this head 25 there is provided a check valve mechanism, so to speak, 42, comprising a ported valve element 43, operative when in seated position to prevent fluid passage in either direction between the space above the head 36 in the bore 30 31 and the bore 1 of the cylinder. Valve 43 is normally maintained seated by a spring 44 and has a projecting stem 45 which is engageable by a hardened plug 46 in the upper end of the head 36 when the distributing valve 35 is in its top 35 position. Accordingly the valve 43 is unseated and permits communication between the space within the cylinder 6 and the space within the bore 31 above the valve head 36, when said distributing valve 35 is in its uppermost position. When, however, the distributing valve is in the 40 position shown in Figs. 2 and 3, the valve 43 is seated, and the spring 44 is strong enough to prevent unseating of the valve and passage of fluid from the space above the head 36 to the space within the cylinder bore above the piston 8 even though that space be under only substantially atmospheric pressure, as is the case during 45 normal pumping operations.

50 The cylinder bore 7 is also connectable, at a considerably lower point, 50, therein, uncovered by the upper end of the piston 8 just about as the latter reaches the desired lower limit of piston travel, with the bore 31 above the head 36, under certain conditions hereinafter described. Tubing 55 55 connects the point 50 with a space 52, within a mechanism 53, hereinafter more fully described, and tubing 54 leads from mechanism 53 to a valve-seat-providing tubular element 55 secured centrally in the head 25. Member 55 provides a 60 valve seat 56, and the head 36 of the distributing valve carries a resiliently positioned valve element 57, which, in the upper position of the distributing valve, engages the seat 56 and prevents flow in either direction between the space within the bore 31 above the head 36 of the distributing valve and the point of communication 50 with the cylinder bore 7. No pressure normally present in the cylinder bore 1 can unseat the valve 57 when the distributing valve is in its upper 65 position. However, when the distributing valve is moved to a position to move the valve portion 57 out of engagement with seat 56, free communication between the cylinder bore at point 50 therein and the top of bore 31 is established.

70 The mode of operation of the device so far described is self-evident. Assume that the parts are all in the position illustrated in Figs. 2 and 3, and it will be clear that the motor piston 8 is still upon its downward pass and has not yet uncovered the point 50 for a sufficiently long period, at least, for the fluid to exhaust to atmosphere from the bore 31 above the valve head 36, and allow back pressure acting upon the lower end of head 39 of distributing valve 35 to raise the latter to fluid admission effecting position. It will be obvious that in the instantaneous position of the parts shown in Figs. 2 and 3, the space above the head 36 is subject to the same pressure that is acting on the lower end of the head 39, for the lower end of the motor cylinder is connected to exhaust, that is to the back pressure against which the motor exhausts, and that same back pressure prevails in the space below the head 39. When the top of the motor piston 8 passes below the connection point 50, the fluid within the bore 31 above the head 36 of the distributing valve will pass through the connections 54, 52 and 51 into the motor cylinder above the motor piston, and there pass to atmosphere since the space above the motor piston is normally substantially at atmospheric pressure, due to the presence of the relief device 11. As soon as the pressure above the valve head 36 has been released, the constant pressure acting on the lower head 39 thereof will raise the distributing valve, and the groove 38 in the latter will move from exhaust-establishing position to admission-effecting position, and motive fluid will be supplied from groove 16 to groove 18 and then through port 19 into the space beneath the piston 8. Obviously, as shown in the drawings, the member 24 must be provided with suitable passages connecting its interior with the several spaces 16, 17 and 18. Upon admission of motive fluid beneath the motor piston the latter commences its upward travel, and when its lower end passes above the connection point 50, cylinder pressure cannot pass to the space above the head 36 of the distributing valve and cause downward movement of the latter, because the valve 57 engages the valve seat 56 and seals off communication between the cylinder bore and the distributing valve chamber bore. The motor piston accordingly continues its upward travel until it passes above the connection point 40, at which time fluid will be enabled to pass through the connection 41 and the then unseated valve 43 to act upon the upper head of the distributing valve and start the latter towards exhaust-effecting position. The pressure passing the valve 43 merely starts the distributing valve upon its downward movement, and the complete throwing movement is effected by pressure which passes from the connection point 50 to the space above the distributing valve as soon as valve 57 moves off the valve seat 56. As soon as the distributing valve assumes the position shown in Fig. 2, release occurs, and the motor piston, under its own weight and that of the supported parts, begins to move downwardly. The downwardly moving motor piston first passes below the connection point 40, and as the space above the motor piston is approximately at atmospheric pressure, the pressure holding the distributing valve in its lower position would be 75 vented were it not for the fact that the valve 43 is engaging its seat and is not unseated by the pressure differential at its opposite sides, the spring 44 being strong enough to prevent this occurring. The motor piston therefore continues

ues its downward movement until its upper end passes beneath the connection point 50, at which time the pressure which has been holding the distributing valve in its lower position will be vented to atmosphere through the valve seat 56, connection 54, space 52, connection 51, the cylinder bore, and the relief device 11. The distributing valve will then again be moved into admission effecting position by the fluid pressure acting upon its lower end from the back pressure line, and another cycle like that which has been described will be started.

As previously pointed out, it is desirable to shut down the motor in the event of sucker rod line breakage or the blowing through of the pump packing, and, therefore, means is provided for accomplishing this function. Such means may take the form shown in Letters Patent No. 2,004,145, which patent shows means for closing the admission and the exhaust lines to the pumping motor, or may assume the form shown in my co-pending application, Serial Number 102,989, filed concurrently herewith. For purposes of illustration I am here showing the latter mechanism and will describe its mode of operation.

Obviously, if the rod line broke during the up-stroke of the motor piston 8, which is evidently the time when such a breakage would occur, if at all, the motor piston 8 would be freed of a substantial part of its load. The pressure acting beneath the motor piston, which is so determined as to provide for the desired speed of upward movement of the motor piston under full load, would obviously be much in excess of that necessary to raise the piston under the then reduced load condition. Therefore, the motor piston would move upward at a much accelerated rate and would pass its normal upward limit of travel, notwithstanding the fact that the condition for release of the working fluid beneath it would be produced as soon as the upward movement of the piston carried it above connection point 40. The motor piston 8 would, therefore, pass up into the cylinder portion 6b and would there be cushioned, building up above it a considerable cushion pressure before it would come to rest. A downward movement of the motor piston would then be initiated, and the piston would move downward to its lower position and then again move up under the admission of line pressure, effected by the reversal of position of the distributing valve as the motor piston approached bottom position, unless some means were provided to interrupt the operation of the motor. Serious damage might be done by an excessively rapid downward movement of the motor piston during even a single stroke, unless means were provided to reduce quickly the cushion pressure or otherwise retard downward movement of the motor piston, and after describing the structure which is employed for the purpose of stopping the motor, I shall describe the improved means which I am disclosing herein for the purpose of reducing the cushion pressure as soon as the motor piston has come to rest and begun to descend.

The means for interrupting operation of the distributing valve 35 and holding the latter in exhaust-establishing position as soon as abnormal operation of the motor begins to take place, includes the device 53 heretofore mentioned, and certain connections which I shall now explain. An additional connection point 60 with the cylinder bore will be provided at such a point that it will be uncovered by the lower end of the upwardly moving piston 8, only when the latter

makes such an extended upstroke as will never occur except in the event of such a derangement as breakage of the sucker rod line or the blowing out of packings on the pump plunger. This connection point will be connected by a suitable tube 61 with a space 62, the supplying of fluid to which will render the automatic shut-down device 53 effective. The shut-down device 53 comprises a valve casing 64 provided with alined bores 65 and 66, of which the latter is somewhat larger and also the upper one. A conical or other suitably formed seat 67 is located at the junction of the bores 65 and 66. Connection 51 enters the bore 65 near the upper end of the latter, and connection 54 communicates with the bore 65 at a point somewhat below the point of communication of the connection 51 with the bore 65. These points of communication are respectively designated herein 68 and 69. A valve element 70 is reciprocably mounted in the bores 65 and 66, and comprises a lower head 71 fitting the bore 65 and an upper head 72 fitting the bore 66; and a conical portion 73 adapted to co-operate with the seat 67 is provided, and also a reduced portion 74 cut away as at 75 to leave the space 52 hereinabove mentioned. Within the bore 66 there is arranged the lower head 77 of a manually operable plunger element 78, whose stem portion 79 passes through an opening 80 in the upper head 81, which closes the top of the bore 66. A manual pressure-applying portion 82 is secured upon the stem 79. A spring 84 is arranged between the enlarged portion 72 of the valve element 70 and the head 71. A latch device 86 is movable between the positions shown respectively in Figs. 4 and 5, and normally holds the head 71 in such a position that the spring 84 will hold the valve 70 in the position shown in Fig. 4, notwithstanding the pressure which may act upon the lower end of the head 71 thereof. A piston 88, reciprocable in a bore 89 formed in the member 64, is movable upon the supply of pressure through the connection 61, to withdraw the latch 86 and release the plunger element 78 for upward movement, thereby relieving the valve 70 of the holding pressure exerted by the spring 84. Connection 61 communicates at 90 with the space 62 formed within the cylinder bore 89, to the inside of the piston 88; and a connection 91 leading to the live pressure space 16 in the valve chest opens into the bore 65 below the valve head 71. Obviously any other means of effecting throwing supply to the valve head 71 might be employed. A connection even with the back pressure line of the pump, having in mind the large size of the head 36 of the distributing valve, would, of course, provide a sufficient pressure to effect the desired operation.

The mode of operation of the apparatus last described may be now readily followed. In the normal position of the controlling device 53, the parts will occupy the positions shown in Fig. 4, the valve element 70 being in its lower position with the portion 73 thereof seated on the seat 67, and the space 52 surrounding the reduced portion 74 of the valve 70, establishing communication between the ports 68 and 69, and the head 71 preventing the flow of line pressure through the connection 91. Assume now that the rod line breaks and that the motor piston rapidly moves upwardly in an extended stroke and passes above the connection point 60. The pressure from beneath the motor piston 8, even though it may have begun to drop as a result of

the over travel of the motor piston, will still be entirely adequate, upon passage through the connection 61 to the space 62, to force the piston 88 outwardly and to withdraw the latch 86 and thereby free the plunger 78 for upward movement, with the result that the compression of the spring 84 will be released. The distributing valve 35 will in all probability already have been moved to exhaust-effecting position and so will merely need to be held there. However, had it not yet so moved, it would be moved as a result of what occurs when the head 77 is unlatched. The live pressure acting upon the lower end of the valve head 77 immediately moves the valve 15 70 up to the position where the head 77 will seal port 68 and will uncover port 69. The live fluid from the space 16 will then immediately pass through 91, through the bore 65 to the port 69, through the connection 54 and the element 55, 20 and through the valve seat 56, into the bore 31 above the upper end of the distributing valve 35, and hold the latter firmly in its exhaust-establishing position, or move it thereto if it has not yet attained such position, and nothing can 25 thereafter move said distributing valve out of its position until the valve 70 is again returned to its position shown in Fig. 4. Fig. 5 shows the parts in the positions they assume after the upwardly moving piston 8 has uncovered the connection point 60. All that is necessary to enable the motor to resume operation, when this is desired, is for the operator to apply pressure to the portion 82, force the plunger 78 downward, move the latch 86 in, and so hold head 77 in the 30 position shown in Fig. 4; and the valve 70, which will have been moved down into its position shown in Fig. 4, will there be maintained, and the operation of the motor can then be started in its normal manner.

40 Now to return to the apparatus for preventing an unduly rapid downward movement of the motor piston and the attached parts, as a result of a building up of a comparatively high cushion pressure during the over-travel of the motor piston in an upward direction. In order that the relatively high pressure so produced shall not continue to exert a pressure on the top of the motor piston and impart to the latter a high downward velocity, I have provided improved 45 means for relieving the cushion pressure as soon as the same has begun to drop due to a reversal of movement of the motor piston. Obviously, if such a control were made merely responsive to the creation of a predetermined maximum pressure within the cushion cylinder, it would be possible that venting might occur prior to the bringing to rest of the piston, and accordingly I prefer to employ a construction in which the 50 relief of the cushion pressure shall be delayed until the motor piston has been brought fully to rest and reverses its motion and begins to move downward, with a resultant slight reduction in the cushion chamber pressure. Because of the 55 peculiar nature of the expansion and compression of air, it will be evident that with a relatively high cushion pressure a very small movement of the motor piston in the downward direction may make a substantial reduction in the 60 pressure within the cushion space, and accordingly the use of this reduced pressure condition will enable a certainty of action and at the same time not permit the imparting by the built-up cushion pressure of a high velocity to the downwardly moving motor piston.

For the purpose of effecting the desired control, I provide means continuously subject to the pressure conditions within the cushion space of the motor cylinder, and adapted to store up energy in the event of the building up of an excess pressure in said cushion space, and to employ said energy upon a reduction in pressure within said cushion space for the purpose of opening vent means leading from said cushion space to the atmosphere or to some other point of low pressure discharge.

Now referring more particularly to Figs. 7 to 11 inclusive on the drawings, the uppermost portion of the cylinder bore 7 within the part 6b of the motor cylinder will be observed to be connected through a suitable connecting and support device 100 with an apparatus which is generally designated 101. This apparatus contains a chamber 102 connected by a passage 103 in the connecting element 100 with the top of the cylinder bore 7; and said space 102 has continuous communication through a port 104 with an elongated fluid reservoir 105, which extends from the top of the device 101 to the bottom of the latter. Apparatus 101 includes a main body portion 106, a top closure element 107, and a lower head element 108, all suitably connected together; and the portion 106 includes not only the reservoir space 105 but a larger, parallel chamber 110. Extending upwardly within the chamber 110 and supported by the lower head 108 is a cylindrical element 111, whose upper end carries an outwardly-opening spring-pressed check valve 112 controlling the communication between a passage 113, which is in continuous communication itself with the fluid reservoir 105, and a space above the end of the cylindrical element 111. Surrounding the member 111 and slidably longitudinally with respect thereto is a hollow spring support member 114 providing a peripheral ledge upon which the lower end of a spring 115 rests. The member 114 is closed at its top, so that its interior 116 constitutes a cylinder bore coacting with the stationary piston, so to speak, 111. The upper end of the spring 115 engages 45 an abutment member 117, which contacts the lower end of the stem 118 of a valve 119, which controls the communication between the space 102 and a space 120 which is in constant communication with the atmosphere through a series 50 of openings 121. The valve 119 is adapted to co-operate with a seat 122 surrounding a passage 123, which when uncovered by said valve 119, connects the chamber 102 freely with the space 120. The upper head 107 contains a spring 124 55 acting upon the top of the valve element 119, and also provides a guide 125 for a reduced cylindrical portion 126 integral herein with the valve 119. The space 105 is desirably filled substantially full with a liquid such as a light oil or the like, and the seat of the valve 112 may be scored or grooved if desired to permit an automatic restoration of the device to working condition after a predetermined period. Since, however, it is important that this device shall be capable 60 of functioning prior to the putting in operation again of the pumping motor, it is as well to omit any means for providing an indefinitely prompt return to operative condition, as serious injury might result were the motor to be restarted with 65 the cushion device inoperative, as it would be if the valve 119 were still unseated.

Now the mode of operation of this apparatus will be readily understood. During the normal reciprocation of the motor piston 8 within the 75

cylinder bore 7, the release device 11 will cause a breathing action to take place, and the differential between atmospheric pressure and the pressure within the space within the cylinder bore 7, 5 will not exceed one or two pounds per square inch. When, however, the sucker rod line breaks, should that occur, or a pump plunger packing ruptures, the motor piston 8 will move rapidly upward past the mouth of the release device 11, and trap fluid in the upper end of the cylinder bore 7, and compress that fluid to a considerable pressure in the course of decelerating. The pressure built up within the bore 7 will pass through the connection 103 into the chamber 102, through the passage 104, and act upon 10 the top of the liquid within the reservoir 105 and force said liquid through the passage 113 and past the valve 112 and raise the slidable spring seat cylinder element 114 upwardly, and place the spring 115 under compression. The valve 119 15 will be formed with an upper area relatively larger than the cross section of the bore of the member 114, and because the pressure acting upon the top of the valve 119 and the pressure acting within the bore 116 will be substantially 20 the same, there will be no effective tendency towards unseating the valve 119 so long as the pressure within the cushion space in the cylinder bore 7 remains unreduced. When the motor piston 8 has come to a stop and begins to move downward, and there is an increase in volume within 25 the space above the piston 8 within the cylinder bore 7, there will be a reduction in pressure within that space. However, the check valve 112 will not permit reverse flow of the liquid 30 which has entered and been trapped in space 116 above the top of the member 111, so there will be no reduction of compression of the spring 115 by lowering of member 114 as the pressure drops within the top of the cushion space. 35 Therefore, a reduction in the pressure acting upon the top of the valve 119, will shortly permit the latter to be unseated by the force exerted by the spring 115, and thereupon the pressure within the upper end of the cushion space in the cylinder bore 7 will be quickly reduced to atmospheric pressure, passing through the passage 103, 40 space 102, port 123, and passages 121, to the atmosphere. After the motor has been shut down 45 the pressure may gradually leak out of the bore 116 above the stationary piston-like element 111, and the parts gradually assume once more the position shown in Fig. 7. Figs. 7, 8, and 9 are interesting in disclosing the mode of operation of 50 this device, in that Fig. 7 indicates the position of the parts during the normal pumping operation, that is, at such times as there is no building up of any substantial pressure within the cushion space in the bore 7. Fig. 8 illustrates 55 the position of the parts assumed when the motor piston has made a rapid and overlong stroke as the result, say, of the breaking of the sucker rod line. Here it will be noted that fluid has been driven down in the reservoir 105, up past the 60 check valve 112, and trapped in bore 116 above the member 111. Because the pressure is still at its maximum value within the space 102, the valve 119, however, remains upon its seat. Fig. 65 9 shows the condition when the cushion pressure has been permitted to lower as a result of a certain amount of re-expansion after the motor piston 8 starts its downward travel. Here it will be observed that the lowered pressure acting upon 70 the top of the valve 119 has permitted that valve 75 to unseat under the pressure of the spring 115.

and to vent to atmosphere the pressure within the cushion space.

From the foregoing description, it will be obvious that I have provided an improved apparatus for cushioning the piston of a pump operating motor in the event of loss of load thereby, and a relieving of the cushion pressure prior to the possibility of the imparting to the piston of a dangerous velocity in an opposite direction. It will further be noted that I have provided an improved motor in which, when through breakage of certain parts, the motor is relieved of its load, the over-travel of the motor piston is duly cushioned and the piston brought to rest and then prevented from obtaining an unduly rapid opposite velocity, and the motor is simultaneously, or practically so, shut down, so that the entire system is put out of operation, after having been brought harmlessly to rest; and the system is maintained shut down until such time as an operator can give it his attention. It will be obvious that the structure provided for controlling the reduction automatically in the cushion pressure is simple, positive in action, certain in operation and comparatively inexpensive in construction. Further I have provided an improved cushion device per se.

While in the accompanying drawings I have disclosed and in the foregoing specification described one species which my invention may assume in practice, it will be understood that the same may be modified and incorporated in various other embodiments without departing from the spirit of the invention or the scope of the appended claims.

What I claim and desire to secure by Letters Patent is:

1. In combination, a single-acting expandable-chamber motor comprising a cylinder, a piston reciprocable therein, and means for effecting supply of motive fluid to one end of said cylinder and the exhaust of fluid therefrom after the same has worked in said cylinder, and means associated with the normally inactive end of said motor cylinder for building up a cushion pressure for cushioning over travel of said motor piston should the same occur and venting the cushion pressure upon a reverse movement of said motor piston.

2. In combination, a single-acting expandable-chamber motor comprising a cylinder, a piston reciprocable therein, and means for effecting supply of motive fluid to one end of said cylinder and the exhaust of fluid therefrom after the same has worked in said cylinder, and means associated with the normally inactive end of said motor cylinder for building up a cushion pressure for cushioning over travel of said motor piston should the same occur and venting the cushion pressure upon initiation of reverse movement of said motor piston.

3. In combination, in a cushion apparatus, a cylinder, a piston movable into said cylinder to build up a cushion pressure, means associated with the end of said cylinder towards which said piston moves and subjected to the pressure conditions therein for placing an energy-storing means in a stressed condition as cushion pressure is built up in said cylinder, and means operable upon a reduction in the cushion pressure within said cylinder, and actuated by said energy-storing means, for venting pressure from said cylinder upon an initial drop in pressure therein.

4. In combination, in a cushion apparatus, a cylinder, a piston movable into said cylinder to build up a cushion pressure, means associated

- with the end of said cylinder towards which said piston moves and subjected to the pressure conditions therein for hydraulically placing an energy-storing means in a stressed condition as pressure is built up in said cylinder, and means operable upon a reduction in the pressure within said cylinder, and actuated by said energy-storing means, for venting pressure from said cylinder upon an initial drop in pressure therein.
- 5 5. In a device of the character described, in combination, a casing having a chamber therein connectable to a space, the pressure in which is to be controlled, another space in communication with the atmosphere, a valve controlling communications between said spaces, and means operable to open said valve upon a pressure drop in said first mentioned space below the maximum value established in the latter including an energy storing device and means operable by pressure transmitted to said first mentioned space for storing energy in said device.
- 10 6. In combination, in a controlling apparatus for a cushioning device, means providing a plurality of chambers one connectable with a cushion space and another connected with the atmosphere, a valve controlling communication between said chambers, a spring operative under certain conditions to exert an opening force on said valve, means operable by pressure from said first mentioned chamber for stressing said spring and maintaining the same stressed irrespective of a later reduction in pressure within said first named chamber, said last mentioned means operable when pressure conditions build up in said cushion space above a predetermined desired maximum, said valve subject to the pressure conditions within said first named chamber and held by said conditions in closed position until after the pressure acting thereon falls below the maximum attained value by a predetermined amount.
- 15 7. In a cushion cylinder controlling apparatus, in combination, a casing having a chamber communicable with a cushion space, said casing further having a chamber therein communicating with the atmosphere, a valve normally maintained closed and subjected to chamber pressure conditions for normally precluding communication between said chambers, and means energized by pressure transmitted to said first named chamber while said valve is closed for creating a pressure acting on said valve in a valve opening direction and maintaining said pressure despite pressure reduction in said first named chamber.
- 20 8. A cushion cylinder, a piston movable in said cushion cylinder, a vent valve for said cushion cylinder subjected to the pressure conditions in the latter in a direction tending to maintain said valve seated, and means operable by pressure conditions created in said cushion cylinder during the cushioning function thereof for creating, while said valve is closed, a valve opening pressure applicable to said valve with undiminished force when said cushion cylinder pressure diminishes, whereby said valve opens upon a falling off in cushion cylinder pressure.
- 25 9. In combination, a pumping motor having a pumping load, and including fluid distribution means, and means automatically operative in the event of loss of motor load for locking the fluid distribution means for said motor in exhaust establishing position, and cushioning means for checking the motion of said motor in the event of the loss of load thereby and after cushioning of the motion of said motor automatically relieving the cushion pressure prior to the establish-

ment thereby of a high motor velocity in a reverse direction.

10. In combination, a pumping motor adapted to raise a pumping load and including a cylinder and a piston reciprocable in said cylinder and a distributing valve for selectively admitting pressure to said cylinder to effect upward movement of the piston in said cylinder and releasing the pressure from said cylinder for the purpose of causing downward movement of said piston, means automatically operative, and controlled by pressure conditions in said cylinder resulting when the motor piston makes a stroke of a length exceeding a predetermined value, for automatically maintaining said fluid distribution valve in exhaust effecting position, and means controlled by such conditions above said motor piston in said cylinder for creating a cushion pressure and automatically venting the same after cushioning is completed and prior to substantial downward movement of said piston.

11. In combination, in a pumping apparatus, a pump operating motor having a vertical cylinder with a piston reciprocable therein and fluid distribution means operative automatically alternately to admit pressure fluid beneath said motor piston and to vent pressure fluid from beneath the same, means operable by pressure from beneath said motor piston when the latter makes a stroke exceeding by a predetermined amount the normal operating stroke for locking said fluid distribution means in exhaust-establishing position, and means governed by pressure conditions in said motor cylinder above said piston for sealing the upper end of said cylinder during cushioning occurring in the event of an unduly long motor stroke and for releasing said cushioning pressure to atmosphere in response to a drop in pressure above said motor piston prior to the attainment by said piston of a substantial velocity in a downward direction.

12. In a dash-pot, a cushioning device operative on performing its cushioning function to produce conditions conducive to a back kick by the same, and means for preventing a back kick by the same including means for relieving cushion pressure on motion in the reverse direction of the device to be cushioned.

13. In combination, a single-acting expandable-chamber motor comprising a cylinder, a piston reciprocable therein, and means for effecting supply of motive fluid to one end of said cylinder and the exhaust of fluid therefrom after the same has worked in said cylinder, energy-storing means for opposing a progressively increasing resistance to piston movement as overtravel thereof in the working direction occurs, and means for releasing the stored energy early in the movement of the piston in a reverse direction following the bringing of the same to rest.

14. In combination, a single-acting expandable-chamber motor comprising a cylinder, a piston reciprocable therein, and means for effecting supply of motive fluid to one end of said cylinder and the exhaust of fluid therefrom after the same has worked in said cylinder, elastic energy-storing means for opposing a progressively increasing resistance to piston movement as overtravel thereof in the working direction occurs, and means for releasing the stored energy early in the movement of the piston in a reverse direction following the bringing of the same to rest.

15. In combination, a single-acting expandable-chamber motor comprising a cylinder, a piston

- reciprocable therein, and means for effecting supply of motive fluid to one end of said cylinder and the exhaust of fluid therefrom after the same has worked in said cylinder, energy-storing means including a body of compressible gas and means for progressively compressing the same for opposing a progressively increasing resistance to piston movement as overtravel thereof in the working direction occurs, and means for releasing the stored energy early in the movement of the piston in a reverse direction following the bringing of the same to rest.
16. In combination, a single-acting expansible-chamber motor comprising a cylinder, a piston reciprocable therein, and means for effecting supply of motive fluid to one end of said cylinder and the exhaust of fluid therefrom after the same has worked in said cylinder, and energy-storing and releasing means both governed by piston movement for opposing a progressively increasing resistance to piston movement as overtravel thereof in the working direction occurs and for releasing the stored energy promptly upon a reversal of piston movement following the bringing of the same to rest.
17. In combination, a pumping motor having a pumping load and including fluid distribution means, means automatically operative in the event of loss of motor load for causing the motor to be connected to exhaust, means for cushioning the resultant travel at a higher speed which follows loss of load, and means for precluding the return to the piston of the energy absorbed in the cushioning thereof.
18. In combination, a pumping motor having a pumping load and including fluid distribution means, means automatically operative in the

event of loss of motor load for shutting down the motor, means for decelerating the piston following loss of motor load, and means for precluding the return to the piston of the energy absorbed in the deceleration thereof.

19. In combination, in a motor, a cylinder, a piston reciprocable therein, means for applying pressure to one end of said piston to cause it to make a working stroke, and means for removing pressure therefrom after said piston has completed its working stroke, means creating a force opposing movement of said piston beyond its working stroke, and means removing said opposing force upon the occurrence of any decrease in said opposing force.

20. In a motor of the character described, the combination of relatively reciprocable cylinder and piston elements, fluid distribution means for supplying pressure fluid to and exhausting fluid from said cylinder element for effecting relative reciprocation of said elements, means inactive during normal operation of the motor and automatically operative in the event of sudden loss of motor load for providing a relatively high cushioning pressure at one end of said cylinder element to check excessive relative movement of said elements in one direction, means automatically operative upon occurrence of abnormal motor operation for automatically rendering said fluid distribution means inactive thereby to shut down the motor, and means operative subsequently to said cushioning action and when such excessive relative movement of said elements in said direction is checked for automatically relieving the cushioning pressure.

WADE H. WINEMAN.

CERTIFICATE OF CORRECTION.

Patent No. 2,159,467.

May 23, 1939.

WADE H. WINEMAN.

It is hereby certified that error appears in the printed specification of the above numbered patent requiring correction as follows: Page 1, first column, line 41, after the word "motor" insert piston; page 5, second column, line 13, for "drawings" read drawing; page 7, first column, line 18, claim 5, for "esablished" read established; line 50, claim 7, for the word "value" read valve; and that the said Letters Patent should be read with this correction therein that the same may conform to the record of the case in the Patent Office.

Signed and sealed this 25th day of July, A. D. 1939.

(Seal)

Henry Van Arsdale,
Acting Commissioner of Patents.
